UNITED STATES PATENT OFFICE.

ALBERT WEICKMAN, OF NEW YORK, N. Y.

SPRING-FRAME FOR CUSHION-SEATS.

1,027,949.

Specification of Letters Patent. Patented May 28, 1912.

Application filed September 23, 1911. Serial No. 650,877.

To all whom it may concern:

Be it known that I, ALBERT WEICKMAN, a citizen of the United States, and a resident of the city of New York, borough of Manhattan, in the county and State of New York, have invented a new and Improved Spring-Frame for Cushion-Seats, of which the following is a full, clear, and exact description.

10 My invention is an improvement in seat cushions, and it aims to provide a novel framework comprising a number of resiliently-connected parts which can be upholstered and covered to give the effect desired. To this end I have devised a construction including a pair of frames rigidly connected to each other, and a third frame with respect to which the first two frames are vertically movable, a plurality of springs 15 being employed to connect the first two frames and the third frame together. The topmost of the first two frames contains a plurality of brace wires which form a support for the body of the seat, these brace wires being resiliently connected to the inside of the frame to form a support or base 20 for the cushion which is placed on top of the frame when the seat is made.

Reference is to be had to the accompanying drawings forming a part of this specification, in which the same characters of reference indicate the same parts in all the views.

Figure 1 is a perspective view of a spring 35 cushion made according to my improved design; Fig. 2 is a top plan thereof. Fig. 3 is a bottom plan thereof; and Fig. 4 is a vertical section on the line 4—4 of Fig. 2.

On the drawings, 1 is a suitable frame 40 which incloses a lower frame 2, movably mounted therein and joined to an upper frame 3, by means of a plurality of posts 4. These posts 4 are preferably connected to the mid points of the sides of the frames 2 and 3, and they serve to support the frame 3 a considerable distance above the upper edge of the frame 1. Numerals 5 indicate a pair of blocks carried on the inside of the frame 1, in position to engage the posts 4 on either 45 side of the same, and form guides for these posts; and 6 are springs, two or more of which are connected to each side of the frames 1 and 2 to limit the amount of movement of the frame 1 with respect to the frames 2 and 3. Suitable eyelet screws may 50 be employed to connect the opposite ends of

the springs 6 to the frames 1 and 2 for this purpose.

The frame 3 has inside the same and adjacent each corner thereof a pair of horizontal springs 7. The springs adjacent each corner of the frame 3 are substantially at right-angles to each other and are connected at their outer ends by means of a ring 8. These rings 8 are connected together by 60 means of brace wires or rods 9, parallel to the sides of the frame, and diagonal rods or brace wires 10. The springs 7 and the brace wires 9 and 10 form a base or support for the yielding material which forms the body 65 of the cushion; and when this material has been suitably inclosed in sheets of cloth acting as a cover, and laid on top of the wires 9 and 10, the entire structure, including the cushion and the frame, is provided with a 70 cover of cloth or leather shown at 11, which gives it a highly finished appearance.

The operation and utility of my improved cushion frame will be apparent from the drawings. The frame 1 may, for example, 80 be supported by the bottom of the chair; and the frames 2 and 3, which are rigidly connected together, will have a certain amount of vertical movement with respect to the frame 1, owing to their connection 85 therewith by means of the springs 6. At the same time, the body of the cushion will be resiliently supported on the wires 9 and 10, owing to the provision of the springs 7, and the result is a very comfortable seat for 90 the convenience of the user.

I wish to have it understood that I may make certain changes in the shape, size and arrangement of the parts, such as fairly fall within the scope of my invention.

Having thus described my invention, I claim as new and desire to secure by Letters Patent:

1. A spring frame of the kind described, comprising a pair of frames, means for resiliently connecting said frames together, said frames having interengaging means to guide the same in their movements with respect to each other, and a third frame supported by the interengaging means of one of said frames to receive the body of a cushion thereon.

2. A spring frame of the kind described, comprising an outer frame, an inner frame inclosed thereby and resiliently connected thereto, supports secured to the outer faces of the sides of the inner frame and located

between the same and the outer frame, guides secured to the inner sides of the outer frame and located on either side of the supports connected to the inner frame, 5 and a third frame mounted upon the supports connected to the inner frame and carried above the same to receive the body of a cushion thereon.

In testimony whereof I have signed my name to this specification in the presence of 10 two subscribing witnesses.

ALBERT WEICKMAN.
